(57) **CLAIM**

The ornamental design for a footwear article, as shown and described.

DESCRIPTION

FIG. 1 is a first side view of a footwear article showing my new design;

FIG. 2 is a second side view thereof;

FIG. 3 is a first side, rear perspective view thereof;

FIG. 4 is a first side, front perspective view thereof;

FIG. 5 is a top view thereof;

FIG. 6 is a front view thereof;

FIG. 7 is a rear view thereof; and,

FIG. 8 is a bottom view thereof.

The broken lines and the half-tone areas within the broken lines in FIGS. 1 through 8 represent portions of the footwear article that form no part of the claimed design.

FIGS. 1 through 4 illustrate the laces of the footwear article in a first position, and FIGS. 5 and 6 illustrate the laces in a second position.
